TELEPRINTER SUBSCRIBER STATION

Otto Moser, Bern, Switzerland

Application March 17, 1953, Serial No. 342,845

Claims priority, application Switzerland March 18, 1952

3 Claims. (Cl. 178—70)

My invention relates to printing telegraphs of the start-stop type in which a keyboard at the transmitting station controls the emission of code pulse combinations through a single channel to the receiving station where the pulse combinations are applied to a pulse-responsive control magnet that causes a translating mechanism to type or print a character corresponding to the particular pulse combination being received at a time.

In the customary subscriber system of this kind, the coil circuit of the control magnet in the receiving subscriber station is connected between the two leads or poles of the communication line energized from the exchange, and the control magnet is actuated directly by the current flowing in the line. Since the magnitude of the line current is small, the power requirements of the control magnet must be kept within correspondingly small limits. As a result, the receiver mechanism controlled by the magnet has a delicate, light-weight construction whose proper adjustment is critical and demands careful attention.

It is an object of my invention to increase the permissible power capacity of the pulse-responsive receiver control magnet in such teleprinter subscriber stations to thereby secure a less difficult and more reliable operation of the receiver mechanism, or to permit a generally more rugged design of the pulse-translating receiver mechanism than heretofore applicable.

To achieve these objects, and in accordance with a feature of my invention, I connect the pulse-responsive control magnet in the teleprinter receiver station into a local excitation circuit and control this circuit by a relay connected in the receiver loop of the transmission line. The power for operating the indirectly controlled pulse-responsive magnet is preferably supplied from the power line by a rectifier as usually available in subscriber stations for energizing the electric equipment or for operating the drive motors of the teletypewriter or printer to be controlled by the magnet.

According to another feature of my invention, I provide the magnet-controlling relay with two coactive relay windings of which one is excited by the code-combination pulses while the other is connected to the local power supply to provide the relay with preexcitation to secure a rapid response to the occurrence of current pauses in the pulse-excited winding.

According to still another feature of the invention, the teleprinter control magnet is equipped with two magnet systems or units acting in a mutually opposed sense upon the same armature, which are alternately energized by the above-mentioned relay to magnetically move the armature in one or the other direction, thus securing an extremely fast response of the magnet by eliminating the necessity for armature biasing springs whose force must be overpowered when the armature is magnetically attracted.

These and more specific features of my invention will be apparent from the embodiments exemplified by the drawing, in which—

Fig. 1 shows schematically a teletypewriter station with a control magnet with a spring-biased armature, and

Fig. 2 is a similar illustration of a similar subscriber station with a modified control magnet not requiring a biasing spring.

The same reference characters are used in both figures for denoting respectively similar elements.

According to Fig. 1, the mechanism R of the illus-

2

trated subscriber station has a control magnet assembly, denoted as a whole by EM, whose armature oscillates in the rhythm of the code pulse trains arriving from the transmitting subscriber station to thereby control the selection and printing of a corresponding type character. The magnet assembly comprises a rigid frame 1 of non-magnetic material firmly secured to a stationary support or housing structure 2 of the receiver mechanism. A three-legged magnetizable core 3 is rigidly mounted on frame 1 and carries an excitation coil 4 on its center leg. The pole faces of the three legs lie in a common plane. The armature 5 of the magnet is disposed in front of the pole faces in the magnetic field produced by the excitation of coil 4. Armature 5 is pivotally movable about a pivot formed by two coaxial pins of which only the upper pin 6 is visible in the illustration. The pivot pins are revolvable in respective bores of frame 1. Armature 5 is normally pulled away from core 3 by a biasing spring 7 which has one end attached to the armature while the other end is secured to an adjusting screw 8. An arm 9 of armature 5 is linked to an axially movable rod 10 which transmits the armature movements to the type-selecting control mechanism proper (not illustrated). Various designs of such mechanisms in start-stop teletypewriters and similar teleprinters for single-channel operation by code pulses, especially of a five-unit code, are known and suitable for use with the invention, the particular design of the mechanism, including the pulse-responsive control magnet, being not essential to the invention. The particular design of the magnet assembly here chosen for illustration is in accordance with the one pertaining to the teletypewriter control mechanism disclosed in my copending application, Serial No. 388,986, filed October 29, 1953, to which reference may be had if desired.

The coil 4 of the receiver control magnet EM is connected into a local excitation circuit whose current source consists of a rectifier GL. The rectifier is connected through a transformer T to a utility power line and may also serve to supply current to the motors or other electrically operated parts of the teletyping apparatus. A resistor W2 for adjusting the local excitation current and a control contact ir are series connected with each other in the local excitation circuit 11 of magnet coil 4.

The control contact ir forms the contact member of a polarized pulse-receiving relay JR whose polarized magnet core is equipped with two relay windings 12 and 13. Winding 12 is connected across the two line terminals a and b of the subscriber station in loop connection with the transmitting pulse contact sk of the station. Hence, when the station is operating as a receiver, the code pulses, arriving through the transmission channel from the exchange, pass serially through winding 12 and the then-closed transmitter contact sk. When the station is operating as a transmitter, the contact sk is opened and closed in accordance with the code combinations to correspondingly interrupt and restore the line current thus transmitting the proper code pulses as current pauses to the exchange. The winding 13 of relay JR is connected to the rectifier GL in series with an adjustable resistor W1 to provide the relay with pre-excitation whose magnitude can be adjusted at resistor W1. Due to this pre-excitation, the relay contact ir is kept in the illustrated circuit-closing position thus energizing the coil 4 of magnet EM from rectifier GL as long as the subscriber station is actively connected to the line from the exchange so that line current is flowing through coil 12.

The pulses (current pauses) being received, or being issued by the transmitter contact sk, disturb the balance condition of relay JR so that it temporarily opens its control contact ir to interrupt the excitation of control magnet EM in the rhythm of the pulses.

It has been found that in apparatus according to Fig. 1, the dependency of the required magnet attraction of the armature upon the mechanical biasing force of the return spring in the control magnet EM tends to have a very unfavorable effect upon the flip-over period of the armature due, especially, to the square-law dependency of the spring force upon the spring deflection.

The embodiment shown in Fig. 2 avoids this deficiency by having the return movement of the armature also

controlled by magnetic force. To this end, the receiver control magnet EM is equipped with two magnet units denoted summarily by EM1 and EM2 respectively, each magnet unit having a core and a coil similar to elements 3 and 4 of Fig. 1. As illustrated in Fig. 2, the unit EM2 serves as the active control magnet while the unit EM1 operates as a return-bias magnet.

The coils of both magnet units EM1 and EM2 are parallel connected in the local excitation circuit 11 energized from rectifier GL under control by the contact member *ir* of the polarized pulse-receiving relay JR. Contact member *ir* coacts with a normally closed contact 15 series connected with magnet unit EM2 through an adjusting resistor W3, and with a normally open contact 16 series connected with magnet unit EM1 through an adjusting resistor W4. The resistors W3 and W4 permit adjusting the excitation current for each unit independent of the other. The armature 5 is disposed between the respective pole faces of the two units EM1 and EM2 to change its position depending upon which of the units is energized at a time.

The polarized relay JR has two differential windings 12 and 13. Winding 12 serves as the control winding and is connected across the line terminal *a* and *b* through the pulse transmitter contact *sk*. Winding 13 provides the relay with pre-excitation and is connected across the output terminals of the rectifier GL.

As in the embodiment of Fig. 1, any code pulses, transmitted to the exchange by operation of contact *sk* or received from the exchange, disturb the balance of relay JR so that contact member *ir* opens the circuit of magnet unit EM2 at contact 15 and temporarily closes the circuit of unit EM1 at contact 16. The resulting alternating build-up and decay of the magnet field causes the armature 5 to oscillate in accordance with the pulse combinations. That is, when the transmitter contact *sk* in the receiving or transmitting station is closed, the magnet unit EM1 is excited from the local power source and attracts the armature; and when contact *sk* is open, the unit EM2 is deenergized and the magnet unit EM1 is energized thus returning the armature to the position of rest.

The apparatus according to Fig. 2, therefore, receives the advantage that the attraction movement of the magnet armature is independent of the return bias, this being due to the elimination of return springs or other biasing means whose force must be overpowered by the magnetic attraction.

It will be obvious to those skilled in the art that various modifications other than those specifically described may be made without departing from the essence of my invention and within the scope of the claims annexed hereto.

I claim:

1. A teleprinter subscriber station, comprising a teleprinter mechanism having a reciprocable control member and having a control magnet, said magnet having two mutually opposed magnet units forming a field space between each other and having a reciprocable armature disposed in said space to be magnetically moved between two positions depending upon which of said units is energized, said armature being connected with said control member for actuating said member, a local power

5 source for energizing said two magnet units, a pulse-responsive relay having a make contact and a break contact series connected between said respective magnet units and said source for alternately energizing said units in response to code pulse combinations, said relay having a control winding, and a pulse-receiving circuit adapted for connection to a teleprinter communication line and connected with said winding.

2. A teleprinter subscriber station, comprising a teleprinter mechanism having a pulse-responsive control magnet, a local power supply connected with said magnet to provide excitation therefor, a pulse-responsive relay having a movable armature, switch contact means actuated by said armature and connected between said power supply and said magnet for controlling said excitation, said relay having two coactive differential relay windings, one of said windings being connected with said local power supply for pre-exciting said relay to provide a magnetic flux therein sufficient to hold said armature in open-circuit position of said contact means, a circuit having terminals for connection to a communication line and including a normally closed pulse transmitter contact as well as said other relay winding, said two relay windings when both excited providing in said relay a resultant differential flux sufficient for attracting said armature to close-circuit position of said contact means to excite said magnet, whereby said magnet is controlled in response to current-interrupting pulse combinations in said circuit.

3. A teleprinter subscriber station, comprising a teleprinter mechanism having a reciprocable control member and having a control magnet, said magnet having two mutually opposed magnet units forming a field space between each other and having a reciprocable armature disposed in said space to be magnetically moved between two positions depending upon which of said units is energized, said armature being connected with said control member for actuating said member, a local power source for energizing said two magnet units, a pulse-responsive relay having a make contact and a break contact series connected between said respective magnet units and said source for alternately energizing said units in response to code pulse combinations, said relay having two coactive relay windings, one of said windings being connected with said local power source, a circuit having terminals for connection to a communication line and including a normally closed pulse transmitter contact as well as said other relay winding, said two relay windings when both excited having in said relay a resultant flux sufficient for closing said break contact, whereby said break contact is opened and said make contact temporarily closed in response to current pauses occurring in said circuit.
